UNITED STATES PATENT OFFICE

DONOVAN H. HARDY, OF MANILA, PHILIPPINE ISLANDS, ASSIGNOR OF ONE-HALF TO
ELBERT E. GRUBBS, OF MANILA, PHILIPPINE ISLANDS

SHOE-LACE KNOTTER

Application filed December 10, 1929, Serial No. 413,106.

This invention relates to shoes and more particularly to an improved means for securing a shoe when worn and forming a knot in its lace.

One object of the invention is to provide a shoe having improved fastening means consisting of a lace applied to the shoe in a special manner and adapted to be firmly tied in a bow-knot.

Another object of the invention is to provide the shoe with a knotted element so associated with the lace that a knot may be easily and quickly formed, and to further so form the knotting element that it may be firmly mounted upon the closure flap or strap of a shoe and the lace retained in proper relation to the knotting element.

Another object of the invention is to so form the knotting element that it will be neat in its appearance and not be unsightly when applied to a shoe.

The invention is illustrated in the accompanying drawings, wherein,

Figure 1 is a perspective view of a shoe equipped with one embodiment of the invention,

Figure 2 is an enlarged perspective view of the knotter shown in Figure 1,

Figure 3 is a longitudinal sectional view 30 through the knotter and shoe strap or flap, taken along the line 3—3 of Figure 1,

Figure 4 is a perspective view showing a modified form of knotter applied to a securing strap of a shoe and illustrating the manner in which a knot is formed in a lace,

Figure 5 is a sectional view taken along the line 5—5 of Figure 4, and

Figure 6 is a view similar to Figure 4 illustrating the manner of tying a lace having free ends.

The shoe which is shown in Figure 1 and indicated in general by the numeral 1 is of the slipper type and includes the usual vamp 2, back 3 and heel 4. A securing strap 5 is provided to extend across the instep and at one end is secured to one side of the back 3 of the shoe while its other end is free and overlaps the other side of the back and tab 6 carried thereby when in a securing position.

From an inspection of Figure 4 it will be

seen that the tab or tongue 6 is folded back and secured to form a loop or eye through which the lace 7 passes. The lace may be formed of ribbon or a strand of any other flexible material desired and is joined at its ends as shown at 8 so that it forms an endless loop.

The flap 5 shown in Figure 1 is of greater width than the corresponding flap or strap 9 shown in Figures 4 and 6 and this strap 5 is cut to provide an intermediate strip 10 and upper and lower strips 11 spaced from the side edges of the strip 10. The knotting device shown in Figure 1 is preferably formed of metal although any suitable material may be used and this knotting device is provided with a tubular shank 12 adapted to fit snugly about the strap 10 as shown in Figure 3 and leading from a head 13 which is arcuate in form and has jaws 14 between which the forward end portion of the flap or strap 5 is firmly gripped when the knotter is set in place with its head between the strips 11. Pressure may be depended upon to hold the knotter in engagement with the strip 10 and free end portion of the flap or a suitable adhesive may be applied to assist in securing the knotter. Since the endless lace extends through the loop 6 and through the flap 5 at opposite sides of the shank 12 and strip 10 it will be retained in proper relation to the shank of the knotter and will be prevented from slipping out of engagement with the flap but when the lace is untied the flap or strap 5 may be swung away from the loop 6 a sufficient distance to allow the slipper to be easily put on or taken off.

In the embodiment of the invention illustrated in Figure 4 the strap 9 does not need to be cut to form spaced strips but its free end portion 15 is widened and has an opening formed therein through which is passed an eyelet or ring 16 having a flange 17 at one end and its other end portion bent to form a clamping flange 18 bearing against a washer 19. By this arrangement the eyelet will be firmly held to the strap. The knotting device 20 is similar in shape to the knotter shown in Figures 1 and 2, and includes a shank 21 and head 22. This knotter may be of solid

formation and is secured within the eyelet in any desired manner. When this form of the invention is employed the lace is passed through the eyelet at opposite sides of the shank 21 and after having one end portion passed through the eye or loop 6 the ends of the lace are joined by being stitched together or in any other desired manner. The lace may slide freely through the eyelet and therefore the strap 9 may be swung away from the side portion of the back carrying the loop 6 a sufficient distance to allow the slipper to be easily put on or taken off.

In the embodiments of the invention illustrated in Figures 1 and 4 the lace consists of an endless strand which may be ribbon or shoe lace of a conventional formation. After the shoe has been put on the strap 5 or 9 is drawn to the securing position shown by drawing tightly upon the portions of the lace which project outwardly at opposite sides of the shank of the knotter. The outer end portion of the lace is then formed into a knot as shown at 23 in Figure 4 and when tightened the portion 24 of the lace will be tightly bound across the strap and a bow formed. The loops of the bow may be again knotted if so desired.

The structure shown in Figure 6 is the same as that shown in Figure 4 except that the lace 25 has free ends and its end portions 26 extend in opposite directions across the shank when the knot 27 is tightened.

Having thus described the invention, I claim:

1. A shoe having an upper including a securing flap, a fastener element carried by said flap and having a shank, and a lace carried by a portion of the upper overlapped by said flap and passed through the flap at opposite sides of the shank of said fastener, and adapted to be tied across the shank.
2. A shoe having an upper including a securing flap, a fastener element carried by said flap and having a shank, and a lace carried by a portion of the upper overlapped by said flap and passed through the flap at opposite sides of the shank of said fastener, the lace being endless and loosely connected with the upper and adapted to be tied across the shank.
3. A shoe having an upper including a securing flap having longitudinally extending side strips and an intermediate strip, the free end of the flap constituting a tab joining the side strips and the intermediate strip terminating in spaced relation to the tab, a knotter having a head fixed to said tab between the side strips and a shank extending from its head and engaged with the intermediate strip, and a lace carried by said upper and passed outwardly between the strips at opposite sides of said shank and adapted to be tied across the shank.
4. A shoe having an upper including a

securing flap having longitudinally extending side strips and an intermediate strip, the free end of the flap constituting a tab joining the side strips and the intermediate strip terminating in spaced relation to the tab, a knotter having a head fixed to said tab between the side strips and having jaws gripping the tab and a tubular shank receiving the free end portion of said intermediate strip, and a lace carried by said upper and extending outwardly at opposite sides of the shank and adapted to be tied across the shank.

5. A shoe having an upper including a securing flap free at one end, a loop at one side of said upper overlapped by the free end of said flap, a knotter carried by said flap and having a shank, and a lace slidably passed through said loop and extending outwardly at opposite sides of said shank and adapted to be tied across the shank.

6. A shoe having an upper including a securing flap free at one end, an eyelet fixed in the free end portion of said flap, a shank extending diametrically of said eyelet and having a head at one end projecting from opposite sides of the shank, and a lace carried by said upper at one side thereof and passed outwardly through the eyelet at opposite sides of said shank and adapted to be tied across the shank.

In testimony whereof I affix my signature.

DONOVAN H. HARDY.
